UNITED STATES PATENT OFFICE.

ALBERT L. REINMANN, OF ALLEGHENY, ASSIGNOR TO THE WESTINGHOUSE ELECTRIC COMPANY, OF PITTSBURG, PENNSYLVANIA.

INCANDESCENT ELECTRIC LAMP.

SPECIFICATION forming part of Letters Patent No. 434,159, dated August 12, 1890.

Application filed November 14, 1889. Serial No. 330,262. (No model.)

To all whom it may concern:

Be it known that I, ALBERT L. REINMANN, a citizen of the United States, residing in Allegheny city, in the county of Allegheny and State of Pennsylvania, have invented a new and useful Improvement in Bottoms for Incandescent-Electric-Lamp Bulbs, (Case No. 316,) of which the following is a specification.

The invention relates to the construction of bottoms for electric-lamp bulbs, and involves certain details in the construction of the same.

The invention consists in certain improvements in the formation of the shell and of the contact-plug, as will be more particularly described hereinafter.

The invention will be described in detail in connection with the accompanying drawings, in which—

20 Figure 1 is a section of the lamp-bottom. Fig. 2 is a plan of the interior of the bottom, and Fig. 3 is a plan of the exterior of the bottom. Fig. 4 is an enlarged section showing the neck of the bulb in position, and Fig. 5 is 25 an elevation of the same.

Referring to the drawings, A represents the main portion of the bottom, which usually consists of a shell of metal, preferably brass or similar material. A bottom plate b, 30 of insulating or non-conducting material, is fastened in the bottom of this shell, this plate carrying at its center a contact-point c. The shell is constructed with a circular rib d, which is designed to be engaged by a corresponding bead on the ends of the arms of the socket in 35 a manner well understood. The shell also has a circular indentation or bead e, which serves as a shoulder against which the bottom plate b rests. The end of the shell receiving the bulb is preferably expanded, as 40 shown at f, for the purpose of receiving the neck of the lamp-bulb. The end of the shell is turned or spun over the bottom plate after it has been inserted, thereby holding it in 45 place.

The bottom plate b is constructed with a central opening h for receiving the central contact-pin k. This is inserted through the opening, and its inner end is upset upon a 50 washer k' for holding the pin firmly. The bottom plate is also provided with a groove

m at its side, gradually narrowing from the inner side to the outer, through which one of the leading-in wires of the lamp is led. This wire is afterward soldered or otherwise secured 55 to the outer shell, the latter being provided with a slot n, in which the wire is laid. The other leading-in wire of the lamp is led through the central contact-pin and soldered at the outer end of the pin, which is for this purpose made concave, as shown at p'.

The portion of the neck of a lamp-bulb which is surrounded by the bottom piece or cup usually becomes very hot by reason of the heat developed in the leading-in wires 65 and in the filament, and as the neck of the lamp is usually fastened into the shell by a cement, as shown at s, the shell is closed and the heat is confined. In consequence the bottom or neck of the lamp-bulb is liable to crack. 70 By providing ventilation at this point this danger is materially lessened. This is accomplished by forming openings r through the shell. These may be conveniently formed by striking the metal inward, leaving the lips p 75 projecting immediately above the bottom plate, or by striking out small pieces of the metal or perforating the shell. These openings afford ventilation and allow the circulation of the air around the neck of the lamp 80 after it has been placed in the bottom, thereby lessening the liability of the lamp to crack at the point where the leading-in wires enter the bulb.

I claim as my invention—

1. In a lamp-bottom, the combination of a shell and bottom plate of insulating material, said shell having a groove formed in its edge for receiving a leading-in wire, substantially as described.

2. In a lamp-bottom, the combination, with a plate of insulating material, of a hollow or perforated contact-plug for the purpose of receiving the leading-in wire having a concave or indented end, substantially as described.

In testimony whereof I have hereunto subscribed my name this 9th day of November, A. D. 1889.

ALBERT L. REINMANN.
